SPRAY GUN WITH PNEUMATIC NEEDLE VALVE CONTROL

Svend Bramsen and Fritz Wahlin, Chicago, Ill.,
assignors to Binks Manufacturing Company,
Chicago, Ill., a corporation of Delaware

Application November 27, 1935, Serial No. 51,764

20 Claims. (CL 299—140.1)

Our invention relates to a spray gun (or other spray appliance allied thereto) of the class in which the material-discharge controlling valve, (or so-called needle valve) is continuously urged toward its closure position by a spring and is opened by the pressure of air on a piston fastened to the needle valve, and in general aims to provide a spray gun of the following characteristics:

(1) A mechanism affording a speedy, positive and full opening of the material valve, in response to the retraction of the trigger which opens the air valve.

(2) A mechanism of this kind which will require only a slight additional retracting pressure on the trigger, in addition to that needed for opening the air valve, for admitting air to actuate the needle-valve retracting piston.

(3) A mechanism for this purpose which will leave the entire part of the needle valve between the usual forward guide for that valve and the pneumatically actuated piston free to flex, so as to avoid a cramping or binding of the needle valve.

(4) A mechanism of this type which will permit a ready adjusting of the effective length of the needle valve, and thereby of the extent of the opening movement of this valve, without tempting a user to tamper with the adjustment.

(5) A mechanism of this type permitting the auxiliary valve for controlling the admission of piston retracting air to be coaxial with the needle valve.

(6) A mechanism of this type which will permit a venting of air from in front of the piston when the retracting pressure on the trigger is relaxed, and which will automatically annul the said venting before the opening of the auxiliary valve which controls the admission of air for actuating the said piston.

(7) A spray gun of the above recited characteristics which will not be materially heavier, more bulky or more expensive than a gun of the same operating capacity in which the needle valve is opened through the action of rigid members interposed between this valve and the trigger of the gun.

Illustrative of the manner in which we accomplish the above recited objects,

Fig. 1 is a central, longitudinal and vertical section of the major portions of a spray gun embodying our invention, with both the air valve and the pneumatic needle valve control assembly shown in elevation, showing the parts as they appear when the trigger is not retracted.

Fig. 2 is an enlargement of part of Fig. 1, with

the air valve as well as the pneumatic needle valve control mechanism shown in central and vertical section.

Fig. 3 is a section similar to Fig. 2, but showing the parts as they appear when the valves have been fully opened in response to a retraction of the trigger.

Fig. 4 is an enlargement of a portion of Fig. 3, and Fig. 5 is an enlargement of the same portion showing the positions of the parts before the trigger was retracted.

Fig. 6 is an enlarged perspective view of the thrust member associated with the vent nipple.

Fig. 7 is an enlarged perspective view of the vent nipple, showing the longitudinal surface grooves on this nipple.

Fig. 8 is a still more enlarged and fragmentary front elevation of the vent nipple.

In the illustrated embodiment, the spray gun body is of the two-part type disclosed in the Bramsen and Wahlin applications #43,244 (filed October 2, 1935) and #47,580 (filed October 31, 1935), in which a forward body part F is attached to the stock S of the rearward body part by a nipple through which air flows from the main air passage M in the said stock.

The forward body part F supports a material nozzle N upon which a cap type air nozzle A is clamped by a retainer ring R threaded on the said forward body part, the discharge from the material nozzle being controlled by a needle valve 13 which extends rearwards axially into a bore 1 formed in the body tail part 2 which connects the rear end of the stock S with the usual depending handle H. This bore 1 has a diametrically contracted forward end portion 1a connected to the main part of the said bore by a rearwardly facing annular shoulder 3, as shown in Figs. 4 and 5 and a port P connects the forward portion of the larger diameter part of the bore 1 with the main air passage in the stock S.

The tail 2 also has a second bore 4 extending through it below and parallel to the bore 1 for housing the tubular body 5 of an air valve which also includes a movable valve member V fast on a valve stem 6 extending slidably forward through the said valve body, the bore 4 being closed at its rear end by a cap C, and a compression spring 24 being interposed between the valve member V and the said cap. When the air valve is opened through rearward pressure of the usual gun trigger T against the valve stem 6, air flows from an air supply passage 7 in the handle into the lower bore 4 and the interior of the

55

tubular body 5 and issues from the latter through ports 8 into the part of the lower bore 4 which is forward from the seat 5a for the valve member V. This air then flows upward through a port 9 into the upper bore 1 and through the port P into the stock passage M.

5 Detachably socketed in the upper bore 1 is a tubular guide (generally designated as 10) which has its rear end closed by a detachable cap 20 and which has a mid-length portion threaded (as at 10a in Fig. 3) into the upper bore 1. This 10 guide has a cylindrical portion 10b fitting the part of the said bore behind the said threaded connection, and also has a larger diametered 15 rear part 10c engaging the rear end of the tail 2 of the gun body.

The part of the said guide forward of its said 20 threaded connection to the gun body is generally shaped like a spool presenting a shank 10d, sufficiently smaller in diameter than the part of the bore 1 which houses it, so that air can readily 25 flow around this shank from the port 8 to the port P, and this spool-shaped part of the guide has an axial bore 11, the main and medial portion of which shank bore has a thrust tube 12 extending slidably through it.

The rear end portion 11a of the said shank bore 11 is enlarged in diameter and has one or more lateral ports 14 leading from it to the exterior of the said shank. This shank bore portion also has its extreme rear end flared to afford an annular seat adapted to be engaged by the diametrically enlarged rear end portion 12a of the thrust tube (as in Fig. 2) so as to 30 prevent air entering the lateral ports 14 from reaching the part of the bore of the guide behind the spool-like shank portion 10d of the said guide.

The forward portion of the bore of this shank 40 10d is also enlarged diametrically for a considerable depth so as to house an annular packing 15 (which surrounds a part of the thrust tube 12) and also to house the rear portion of a tubular gland 46 which is threaded into the enlarged 45 forward portion of the said bore and which gland clamps the packing 15 against the annular bottom of the said enlarged forward bore portion. This forward shank portion also has its extreme forward end portion 10b (Fig. 4) fitted into the 50 frontal contracted portion 1a of the said upper bore 1 in the tail of the gun, and has a somewhat more rearward peripheral flange 10f which clamps an annular gasket g against the previously recited shoulder 3 when the said tubular 55 guide is screwed into the tail bore 1 until the head end 10c of that member engages the rear of the body tail.

The more rearward exteriorly cylindrical portion 10b of the said guide has a cylindrical bore 60 part slidably housing a piston through which the rearward portion of the needle valve 13 extends and to which that valve is adjustably fastened. This piston includes a metal stem 16 through which the needle valve is threaded, this stem 65 having a peripheral flange 16a intermediate its ends, and the needle valve being locked to the said stem by a locknut 17 threaded on this valve behind the said stem.

Bearing rearwardly against the flange 16a is a 70 forwardly open cup-shaped piston ring 41 (of leather or the like) which has its annular cup-bottom portion clamped against the forward face of the said flange by a ring 18 sleeved on the stem 16 behind a nut 19 threaded on the forward portion of that stem, as shown in Fig. 2.

The cap 20 which is threaded into the rear end of the said tubular member has a diametrically enlarged portion 20a bearing against the rear end of the said member, to limit the extent to which the cap is screwed into that member, and this cap also has a vent bore 20b in its rear end 5 20c to permit the escape of any compressed air which might seep past the piston ring 41 into the interior of the cap. Moreover, the cap 20 is of such length that its forward end will engage the piston flange 16a to limit the rearward movement of the piston (as shown in Fig. 3) and a compression spring 21 interposed between the piston flange 16a and the rear end 20c of the cap continually urges the piston forwardly. 15

With the bore of the slidable tube 12 considerably larger than the diameter of the needle valve 13, and with the wiper 28 made of flexible material, the needle valve is positively guided only by the usual guide bore 3 in the forward 20 body part and by the piston, thus leaving the intervening major part of the said valve free to flex, so as to prevent a cramping or binding of the needle valve in case this is not exactly straight axially. So also, by providing a wiper 25 arrangement for effectively sealing the forward end of the said slidable tube we could prevent the escape of air through the bore of that tube, from the cylinder space in front of the piston, when the gun is in operation. However, when the tube 12 is slid forward to shut off the admission of further air into the piston cylinder through the ports 14, the residual compressed air in the cylinder in front of the piston, which could not issue through the tube past the wiper 30 members, would act on the piston to prevent a speedy and complete forward movement of the piston for causing the needle valve to close the discharge port of the material nozzle, if no means 35 were provided for venting such air. 40

In the absence of a suitable venting provision, a releasing of the retracting pressure on the trigger, while allowing the spring 24 to close the air valve promptly, would permit material to be ejected for some time after; and this material 45 would splash out unatomized so that some of it would harden on the front of the material nozzle and in the discharge port of that nozzle to gum the needle valve to this nozzle. To avoid these serious objections, we provide the following provisions for permitting residual compressed air in the piston cylinder to vent through the bore of the slidable tube, and for automatically 50 annulling such venting as soon as the gun is again operated: 55

Threaded upon the forward end of the slidable tube 12 is a vent nipple 25 (Fig. 4) which is locked to that tube by a locknut n behind the said nut. This vent nipple 25 has a peripheral flange 25a on its forward end, and has longitudinal surface grooves 25b extending along its shank and opening through the said flange, (as shown in Fig. 7), and the forward portion of the vent nipple is housed by a stop nipple 26 threaded into the rearward portion of a rearwardly opening cap nut 27. This cap nut has its head 27a provided with an axial bore 27b through which the needle valve 13 freely extends, and the stop nipple 26 has at its rear end an interior flange 26a disposed behind the peripheral flange 25a on the vent nut. 60 65 70

The cap nut 27 houses an annular wiper 28 (of leather or the like) which has its radially outer portion 28a bearing forwardly against the axially perforated head 27a of the cap nut, and 75

which wiper has its radially inner portion formed as a rearwardly tapering frustum of a hollow cone fitted upon the portion of the needle valve 13 which extends axially through the cap nut.

Disposed behind this wiper is a presser member; a tubular shank 29 having an axial bore through which the needle valve freely extends, and which has at its forward end a peripheral flange 29, this being clamped against the cap nut head 21a by the shank of the stop nipple 26.

This tubular shank 29 of the presser member has the forward portion 29b of its bore flaring forwardly to fit against the hollow conical part 28 of the wiper, while the peripheral portion of the rear end of the said shank 29 tapers rearwardly and is adapted to fit against a forwardly flaring seat 25c at the forward end of the bore of the vent nipple 25. Thus assembled, the cap nut 21, the wiper and the presser member constitute a presser member through which rearward pressure of the trigger can be transmitted to the vent nipple 25 and hence to the tube 12, the rear end portion of which tube controls the admission of compressed air through the port 14 to the piston cylinder.

To complete the automatic venting provision, we interpose a compression spring 30 between the flange 29a of the thrust member and the frontal flange 25a on the vent nipple 25, which spring 30 continually tends to slide the said presser member forwardly; and a second and strong spring 31 (interposed between the lock nut n and an inferior flange 46a on the gland 46) which spring 31 continually tends to slide the tube 12 forwardly toward the position of Fig. 2 in which the rear end portion of this tube prevents air from entering the piston cylinder. These springs 30 and 31 are each so light that their joint strength is considerably less than that of the spring 21 behind the piston. Moreover, the just described assemblage is so proportioned in the length of its parts (longitudinally of the needle valve) that the head 21a of the cap-nut of the presser member will be spaced rearwardly from the trigger T of the gun even when the trigger first engages the stem of the closed air valve as shown in Figs. 1 and 2.

When our spray gun is not being operated, the intermediate spring 31 holds the sliding tube 12 in its forward position of Fig. 2, so that the rear end portion of this tube effectively closes the air ports 14 leading to the piston cylinder. At the same time, the lighter forward spring 30 holds the thrust member (namely the wiper and the parts supported by the latter) as far forward from the said tube as the engagement of the inferior flange 26a (on the stop nipple 26) with the flange 25a of the surface-grooved vent nipple 25 will permit; so that the grooves in the last named nipple, together with the spacing of that nipple from the thrust member 29 afford a free connection of the outer air to the bore of the tube 12.

When the gun trigger is retracted, it first opens the air valve V and then must compress the (lightest) forward spring 30 sufficiently to permit the tubular shank part 29 of the said thrust member to engage the vent nipple 25 before the trigger starts to move the tube rearwardly, thus affording a time interval (after air is supplied to the air passages of the gun) before air can be admitted to the piston cylinder by a trigger retraction sufficient for compressing the stronger intermediate spring 31 also. Then, as soon as the flaring rear end portion 12a of the slidable tube 12 leaves its seat, air admitted to the piston cylin-

der through the ports 14 almost instantly moves the piston rearwardly until the piston flange 16a engages the forward end of the closure cap 20 behind the piston.

By making the joint strength of the springs 30 and 31 much less than that of the spring 21 which continually urges the piston forwardly, and also considerably less than that of the air-valve closing spring 24, we enable our spray gun to be operated with a quite light digital pressure 10 on the trigger. When this trigger pressure is released, the rear spring 21 immediately slides the piston and needle valve forward. The intermediate spring 31 likewise slides the tube 12 forward for effectively closing the air inlet ports 14 leading to the piston cylinder; and the forward spring 30 slides the wiper 28 and the parts supported by the latter forward to their idle position of Fig. 5, thus permitting residual compressed air in front of the piston to vent by flowing along the arrow lines shown in that figure.

With our spray gun thus constructed, a detaching of the cap 20 from the piston cylinder allows the piston and needle valve assembly to be slid rearwardly to expose the piston behind the said cylinder for adjusting the effective length of the needle valve without disassembling any parts. And when the needle valve and piston assembly is thus detached, a detaching of the trigger from the gun body (in the well known usual manner) 30 also permits a ready detaching of the cap nut 21 of the presser member for replacing the wiper 28 when the latter becomes worn.

By forming the tube guide 10d as an integral extension of the piston cylinder we allow air to 35 enter this cylinder through one or more quite short ports leading directly from the main air passage 9 of the gun; and by forming the guide 10d for the control tube 12 as an integral extension of the said cylinder we simplify the construction and reduce the weight of the gun in comparison with the previously proposed use of a separately attached control cylinder. Moreover, most of the parts which together effect the 40 automatic venting of the piston cylinder are 45 simple and inexpensive screw machine products.

However, while we have heretofore described our invention in connection with a spray appliance having a manually actuatable trigger, and as including numerous desirable details of construction and arrangement, many changes might obviously be made without departing either from the spirit of our invention or from the appended claims.

We claim as our invention:

1. In a pneumatic spraying appliance of the class in which a rod-like needle valve is longitudinally moved rearwardly for opening the discharge of material, and in which the body of the appliance has a bore coaxial with the needle valve; a rearwardly closed cylinder mounted in the said bore and housing the rear end portion of the said valve, a piston fast upon the valve and slidable in the said cylinder, a spring interposed between the piston and the rear end of the cylinder for continually urging the piston forwardly; the cylinder having a tubular guide of relatively smaller bore coaxial with and extending forwardly from the cylinder and connected to the cylinder by an annular portion presenting a rearwardly facing annular valve seat; a tube longitudinally slidable in the said guide and through which tube a part of the needle valve extends, the tube having a rearward portion adapted to seat on the said valve seat; the said tube and

- guide being so formed as to afford an annular space around a part of the tube forward of the said seat when the said tube part is thus seated; the gun body having an air passage, and the 5 guide having an air port leading from the air passage to the said space.
2. A pneumatic spraying appliance as per claim 1, in which the bore of the said tube is considerably larger in diameter than the part of the 10 needle valve which extends through it, so as to permit air to vent through the tube from the part of the cylinder in front of the piston; the appliance also including means responsive to the position of the said tube with respect to the said 15 guide for controlling the said venting of air.
3. A pneumatic spraying appliance as per claim 1, including spring means operatively interposed between the said guide and tube, the said means continually urging the tube forwardly and being 20 weaker than the said piston-urging spring.
4. A pneumatic spraying appliance as per claim 1, including a rearwardly openable air valve controlling the admission of air to the said passage and having a forwardly extending stem, an actuating member movably supported by the appliance body and extending in front of both the said 25 stem and the said tube; a compression spring interposed between the said actuating member and the said tube, through which spring a rearward movement of the actuating member moves the tube rearwardly, and a second spring operatively interposed between the tube and the said 30 guide for continuously urging the tube forwardly, the said compression spring being of less strength 35 than the said second spring.
5. A pneumatic spraying appliance as per claim 1, including a rearwardly openable air valve controlling the admission of air to the said passage and having a forwardly extending stem, an actuating member movably supported by the appliance body and extending in front of and disposed 40 for engaging both the said stem and the said tube; thrust-transmitting means operatively interposed between the forward end of the tube and the actuating member, through which means a rearward movement of the said member moves the tube rearwardly, the said means including a part 45 slidably supported by the needle valve.
6. A spray gun of the class in which a gun body supports a material nozzle, the discharge 50 from which nozzle is controlled by a spring-closed needle valve fastened to a pneumatic piston slidable in a cylinder supported by the gun body, in which the cylinder has an air port leading 55 to its forward portion, and in which a movable trigger depends from the body in front of the said cylinder; the spray gun being characterized by including a generally tubular member extending slidably through the forward head of 60 the cylinder, through which member the needle valve extends; the said member having a rearward part adapted simultaneously to engage the forward head of the cylinder for limiting the forward movement of the said tubular member and 65 to shut off the admission of air to the cylinder through the said port; a thrust member slidably supported between the trigger and the tubular member for transmitting rearward movement of the trigger to the tubular member; and spring 70 means associated with the said tubular member for continuously urging the tube forwardly.
7. A spray gun as per claim 6, including a compression spring interposed between the tubular member and the thrust member for continually 75 urging the thrust member forwardly, the said

two members having portions thereof formed for affording a passageway between them through which air in the said tube can vent out when the needle valve is spring-closed.

8. A spray gun of the class in which a rearwardly slidable material-discharge controlling needle valve is fastened to a piston which slides in a cylinder, in which the said cylinder has a port for admitting air in front of the piston, in which an air valve controlling the supply of air 10 to the said port is openable by rearward movement of a movable trigger through which the needle valve freely extends, and in which a spring continually urges the piston forwardly; the spray gun being characterized by also including a tube 15 coaxial with the needle valve and extending slidably through an axial bore in the forward head of the cylinder, the said tube having a rearward part adapted to seat in the rear end of the said bore for preventing the admission of air to the 20 cylinder from the said port when the needle valve is not slid rearward from its material discharge halting position; a second spring continually urging the tube forwardly, and means slidably upon the needle valve and operatively interposed between the trigger and the tube for transmitting a rearward movement of the trigger to the tube. 25

9. A spray gun as per claim 8, in which the said interposed means include provisions for effectively closing the forward end of the tube 30 when the tube is moved rearward for permitting air to enter the cylinder through the said port, the said provisions being arranged for permitting air to vent through the tube from the part of the cylinder in front of the piston when the tube 35 is in a forward position in which the said rearward part of the tube prevents the flow of air from the said port to the cylinder.

10. A spray gun as per claim 8, in which the said interposed means include a trigger-thrust 40 receiving member slidably supported by the needle valve, two annular elements respectively fast with respect to the trigger-thrust receiving member and the said tube, and a compression spring interposed between the said two elements. 45

11. A spray gun as per claim 8, in which the said interposed means comprise a rearwardly open cap-like trigger-thrust receiving member having its cap head provided with a central bore through which the needle valve freely extends, 50 an annular wiper housed by the said member and slidably fitted upon the needle valve, and means clamping the wiper to the said member.

12. A spray gun as per claim 8, in which the said second spring is sufficiently weaker than the 55 spring means which urge the tube forward so that the rearward movement of the trigger will open the air valve before it begins to move the tube rearwardly.

13. In a spray appliance in which a material-discharge controlling needle valve is fastened to a piston slidable in a cylinder, in which a spring behind the piston continually urges the piston forward, and in which a movable trigger extends in front of the said cylinder: a cylinder having 65 a smaller diameter sleeve coaxial with and extending forwardly from the forward head of the cylinder part way toward the trigger; a tube extending slidably through the bore of the said sleeve, the tube having a diametrically enlarged 70 rear end adapted to engage the forward head of the cylinder to limit the forward movement of the tube; the rear end portion of the bore of the sleeve being enlarged to afford an annular air chamber around the part of the tube in 75

front of the enlarged rear end of the tube, and the sleeve having a port for admitting air to the said chamber; a second spring, weaker than the piston-urging spring and operatively interposed 5 between the said sleeve and the tube for continually pressing the tube forwardly; and movement-transmitting means disposed between the tube and the trigger for transmitting a rearward movement of the trigger to the tube, the said 10 means including an annular wiper slidably fitted upon the needle valve.

14. A spray appliance as per claim 13, including a third spring operatively interposed between the said tube and the movement-transmitting 15 means, and means operatively interposed between the tube and the movement-transmitting means for limiting the forward movement of the said means with respect to the said tube.

15. In a spray appliance in which a material- 20 discharge controlling needle valve is fastened to a piston which is continually urged forwardly by a spring and which piston is slideable in a cylinder, a sleeve coaxial with and extending forwardly from the forward head of the cylinder 25 and having a bore of smaller diameter than the cylinder; a tube extending slidably through the bore of the sleeve, the tube having a head at its rear end and the sleeve having a port for admitting air to the cylinder, which port is oper- 30 atively controlled by the position of the said rear tube head, and the forward end portion of bore of the sleeve being enlarged in diameter; an annular packing sleeved upon the tube and engaging the bottom of the said enlarged bore portion; a tubular gland threaded into the said 35 enlarged bore portion and clamping the packing against the bottom of that bore portion; a compression spring bearing rearwardly against a part of the said gland; an element fast on the 40 tube and engaging the forward end of the said spring; a trigger movably supported forwardly of the said element, and means interposed between the said element and the trigger for transmitting rearward movement of the trigger to the 45 tube.

16. A spray appliance as per claim 15, in which the said interposed means comprise an annular element fast upon the forward end of the tube, a second annular element disposed for- 50 ward of the aforesaid member, a compression spring interposed between the said members, and means sealing the second annular element to the needle valve; the said two elements having interengageable portions for limiting the move- 55 ment of the second element forwardly away from the first named member, and also having annular interengageable portions disposed both for limiting the rearward movement of the first named element with respect to the said second 60 member and for sealing the two elements to each other to cooperate with the sealing of the second element to the needle valve in preventing air in cylinder from venting forwardly through the bore of the tube; the said two elements also 65 being relatively so formed as to permit air issuing from the bore of the tube to vent when the said annular interengageable portions are not engaging each other.

17. In a spray appliance in which a needle 70 valve is moved in its opening direction by the rearward pressure of air on the piston which is slideable in a cylinder, in which a spring continually urges the piston forwardly, in which air is admitted to a forward portion of a cylinder 75 through a port leading from an air passage, and

in which the supply of air to this air passage is controlled by an air valve which is openable by rearward movement of a trigger through which the needle valve freely extends, means whereby the said rearward movement opens the said port 5 at a time interval after the trigger has opened the air valve; the said means comprising a tube extending slidably through the forward head of the cylinder, the tube having a diametrically enlarged rear end portion adapted to seat on the 10 said head for limiting the forward sliding of the tube and halting the flow of air into the cylinder from the said port; spring means weaker than the said piston-urging spring and continually urging the tube forwardly; a thrust-trans- 15 mitting instrumentality operatively interposed between the tube and the trigger and movable towards and away from the tube, and means as- 20 sociated with the tube and the said instrumentality for limiting the extent of the movement 25 of the said instrumentality with respect to the tube in both directions longitudinal of the tube.

18. In a spray gun in which a needle valve is retractile by air pressing rearwardly against a piston fastened to the said valve, and in which 25 the needle valve extends freely through a trigger disposed forwardly of the piston, a longitudinally slideable tube coaxial with and freely housing a portion of the needle valve and disposed be- 30 tween the trigger and the piston, and means for transmitting a rearward movement of the trigger to the tube; the said means comprising: an annular member fast on the forward end of the tube and having a peripheral flange; a trigger-thrust receiving member comprising a rearward- 35 ly open cap-like element having its cap top pro- 40 vided with an axial bore through which the needle valve extends; a nipple threaded into the said cap-like element and having an interior flange disposed behind the peripheral flange on the said annular member; and a compression 45 spring operatively interposed between the said annular member and the cap-bottom of the said cap-like member; the said annular member having longitudinal surface grooves to permit air to 50 flow past both of the said flanges when the said flanges are in engagement with each other.

19. In a spray gun, an assemblage as per claim 18, including an annular wiper housed by the cap-like element, the wiper having its radial- 55 ly outer portion bearing forwardly against the cap bottom of that member and having its bore engaging the needle valve, and an annular presser member bearing forwardly against the wiper, the wiper being clamped between the presser mem- 60 ber and the cap bottom of the cap-like element by the said nipple, and the presser member having a rearwardly extending tubular shank adapted to be moved into and out of engagement with the said annular member respectively by rearward and forward movements of the presser member 65 with respect to the said annular member.

20. In a spray gun in which a needle valve is fast upon a piston which slides in a cylinder, a tubular member coaxial with and freely housing 65 a part of the needle valve and extending slidably through the forward head of the cylinder; the cylinder having a port associated with its forward head for admitting air in front of the piston; and the tubular member having a rearward part 70 adapted to engage the said cylinder head to limit the forward sliding of the tubular member and simultaneously therewith to halt the said admitting of air to the cylinder; the tubular member having a peripheral flange at its forward end; a trigger 75

depending in front of the said tube, through which trigger the needle valve freely extends; and means for transmitting rearward movement of the trigger to the said tubular member and for controlling a venting of air from the cylinder through the said tube; the said means comprising an annular trigger-thrust-receiving member including an annular wiper sleeved upon the needle valve, a presser member disposed behind and fast with respect to the wiper and having a rearwardly extending tubular stem, the rear end of the

said stem being exteriorly frustro-conical and adapted to seat against the forward end of the bore of the said tubular member and a compression spring interposed between the presser member and the forward end of the tubular member, and means interposed between the trigger-thrust-receiving member and the tubular member for limiting the movement of the last mentioned two members away from each other. 5

SVEND BRAMSEN. 10
FRITZ WAHLIN.
